UNITED STATES PATENT OFFICE.

JOSEPH M. GIBEAU, OF MESABA, MINNESOTA.

CORE-BARREL FOR DRILLING-MACHINES.

1,179,173.

Specification of Letters Patent.

Patented Apr. 11, 1916.

Application filed May 27, 1915. Serial No. 30,861.

To all whom it may concern:

Be it known that I, JOSEPH M. GIBEAU, a citizen of the United States, residing at Mesaba, in the county of St. Louis and State of Minnesota, have invented certain new and useful Improvements in Core-Barrels for Drilling-Machines, of which the following is a specification, reference being had therein to the accompanying drawing.

10 My invention relates to improvements in core-barrels for drilling machines.

The object of my invention is to provide a core-barrel for a diamond drill having means whereby water is supplied to both the outside and inside of the core-barrel and at the same time providing means for allowing a circulation of water from the inside of the core-barrel to the outside.

Another object of my invention is to provide a simple, cheap and more effective construction adapted to accomplish the above results and having certain details of structure and combination of parts hereinafter more fully set forth.

25 Referring now to the drawings—Figure 1 is a vertical sectional view of my improved core-barrel attached to the drill stock and also showing the diamond drill head attached. Fig. 2 is a transverse horizontal 30 sectional view taken on the line $x-x$, Fig. 1, and looking downward. Fig. 3 is an enlarged side elevation, partly broken away, of the auxiliary core-barrel.

Referring now to the drawing, 1 represents the internal core-barrel having at its lower end the reduced portion 1', screw-threaded and having screwed thereon the diamond carrying drill head 2, and which barrel, together with its attachment, forms 40 the bit of the boring machine. The upper end of the core-barrel 1 is internally enlarged at 2' and internally screw-threaded. Into this screw-threaded portion the reduced threaded portion 18' of the stock 18 is screwed, so as to bring the outer faces of the barrel and the stock flush, as fully shown in Fig. 1 of the drawings. The upper end of the stock 18 is operated in the usual manner, as is well understood by those skilled 45 in the art and needs no further description.

Within the core-barrel 1 is an inner auxiliary core-barrel 3, having corrugations 4 on its outer periphery, which extend the entire length thereof. These corrugations, as 50 shown in Fig. 2, of the drawings, are on two opposite sides and the remaining two oppo-

site sides being left blank, as indicated at 5 and 5', Fig. 2 of the drawings. This barrel is designed to fit snugly within the outer barrel and to have two holes 6 6' extending through the blank sides 5 and 5', which openings register exactly with the two smaller openings 7 and 7' extending through the walls of the outer core-barrel 1, as shown in Fig. 1 of the drawings.

When the inner auxiliary core-barrel 3 is in place within the outer barrel 1, a tapering plug 8, is fitted within each of the holes formed by the registration of the holes 6 and 7 and designed to be forced tightly 70 therein so as to cause its extreme ends to terminate flush with the outer extremities of the holes, thus firmly locking the two barrels together. When the barrels are thus united, the lower end of the inner auxiliary 75 core-barrel 3 terminates within a short distance of the lower end of the outer core-barrel 1, forming a space between the ends of the barrel and the inner shoulder 3' of the drill head 2, when the latter is up tight 80 against the end of the outer core-barrel. This space 9, as fully shown in Fig. 1 of the drawings, is for the purpose of allowing the free discharge of water from the grooves or corrugations 4, within the walls of the 85 inner barrel 3 and between it and the outer barrel 1. The plugs 8 are each provided through their centers with a passageway or holes 10, the purpose of which will be later described.

The upper end of the inner core barrel 3 is screw-threaded at 11 and has screwed therein the plug 12, which has a downwardly projecting barrel portion 13, extending beyond the threaded portion 11. Two opposite walls of the barrel portion 13 have formed therein openings 14, which communicate with the openings 10 in the plugs 8. The interior of the barrel portion 13 is fitted with any desired form of wire screen 15 to prevent the passage of granular material through the openings 10 with the water. The upper end of the plug 12 is formed with a rectangular recess 16 adapted to receive a plug wrench whereby the same may be readily screwed into or removed from the inner core-barrel 3, as will be readily understood. The stock 18 of the drilling machine, as heretofore stated, is screwed into the outer core-barrel 1, and is of a hollow form so as to 105 provide means for supplying water to the drill, as will be later described.

From the foregoing description it will be seen that the stock 18 is supplied with water which passes downwardly therethrough and enters the upper ends of the grooves 4, between the inner barrel 3 and the outer barrel 1. The water then passes downwardly through the grooves and inwardly through the space 9 at the lower end of the barrel, at a point just above the diamond drill head 2, and is thus fed uninterrupted to a point adjacent the grinding end of the bit. Some of the water passes downwardly and out around the end of the bit on the outside thereof. The remainder of the water will pass on up around the core 19 and from the upper end thereof and through the screen 15 and out through the openings 10 to the outside of the core-barrel 1, and downwardly to the outside of the bit. This will insure a perfect feed of the water to all of the working parts of the drill and thus produce a drill having the greatest possible efficiency.

Having thus described my invention, what I claim and desire to secure by Letters Patent is:

1. A drill of the character described, comprising an outer core-barrel, an inner core-barrel terminating above the lower end of the outer core-barrel and having a plurality of longitudinally extending grooves in the outer surface thereof, a drill head screwed upon and abutting against the lower end of the outer core-barrel, whereby a water discharge space is formed intermediate the lower end of the inner core barrel and the upper edge of the inner wall of the head, a plug within the upper end of the inner core-barrel, and having a chamber therein communicating with a plurality of openings through the core-barrels to without the outer core-barrel, means within the chamber for preventing the openings therein becoming fouled with granular material, the head of the plug fitting down snugly over the upper end of the inner core-barrel, but in such a manner as to leave readily accessible

the upper ends of the longitudinal grooves, whereby water may freely circulate therethrough to the cutting head of the drill as and for the purpose described. 50

2. The combination with an inner core-barrel for drills having formed upon the major portion of two sides thereof a plurality of longitudinally extending water circulating grooves and the other two sides formed the full size of the outside diameter of the barrel, an outer core-barrel having a bore in which the inner core-barrel snugly fits the abutting portions of the two barrels having registering openings extending therethrough, which openings occur on the outside diameter of the inner core-barrel where the said core-barrel has its full size, and means within the openings for fixing the inner and outer barrels rigidly together. 60 65

3. A drill of the character described, comprising an outer core-barrel, an inner core-barrel, the inner core-barrel terminating above the lower end of the outer core-barrel, a drill head carried by the lower end of the outer core-barrel, continuous longitudinally extending grooves from the upper end of the inner core-barrel to the lower end thereof, a plug within the upper end of the core-barrel and having a chamber therein communicating with the interior of the inner core-barrel, means within the chamber for preventing the openings therein from becoming fouled with granular material, the said inner and outer core-barrels having registering openings communicating with the said chamber for passing off an accumulation of liquid from the chamber to the outside of the outer core-barrel, the parts arranged as and for the purpose described. 70 75 80 85

In testimony whereof I hereunto affix my signature in the presence of two witnesses.

JOSEPH M. GIBEAU.
